UNITED STATES PATENT OFFICE.

HOWARD GREER, OF LAKE VIEW, ILLINOIS.

SPLICER-BAR.

SPECIFICATION forming part of Letters Patent No. 354,898, dated December 28, 1886.

Application filed August 16, 1886. Serial No. 211,078. (No model.)

To all whom it may concern:

Be it known that I, HOWARD GREER, a citizen of the United States, residing at Lake View, in the county of Cook and State of Illinois, have invented a new and useful Railroad-Rail Connection or Splice-Bar; and I hereby declare the following to be a full, clear, and exact description thereof, reference being had to accompanying drawings, making a part of this specification, in which like letters indicate like parts.

My invention relates to improvements in such splice-bars as are produced by the well-known methods of rolling, particularly such bars as hold the rails together by means of bolts passing through them and the rails. Such splice-bars are largely made of old iron rails, a material which is rapidly disappearing from the market. Bessemer and similar steels seem to be the "coming" splice-bar material. The use of Bessemer steel for this purpose has been retarded by its brittleness, which causes the splice-bars to break so easily through the bolt-holes.

To obviate this serious defect in splice-bars made of steel and brittle iron is the object of my invention, which I accomplish by the novel channel splice-bar illustrated in accompanying drawings, in which—

Figure 1 is a perspective view showing a complete rail-joint of two channel angle splice-bars bolted to two rails. Fig. 2 is a perspective view showing a detached angle splice-bar differing slightly from that shown in Fig. 1. Fig. 3 is a perspective view of a flangeless or plain channel splice-bar. Figs. 4 and 5 are cross-sections of the front channel angle splice-bar of the rail-joint, Fig. 1, taken through the dotted lines $x\ x$ and $x'\ x'$, respectively. Figs. 6, 7, 8, and 9 are cross-sections of Figs. 2 and 3, taken through the dotted lines $x^2\ x^2\ x^3\ x^3$ of Fig. 2, $x^4\ x^4$ and $x^5\ x^5$ of Fig. 3, respectively.

The channels or grooves begin at C, Figs. 1 and 3, which is the middle of the bar lengthwise, and run to each end, broadening upward and downward or diverging from a mere line in the middle of the splice to a broad groove, which extends almost from side to side of the upright parts of the splices at their ends A and A', Figs. 1, 2, and 3, said channels being of uniform depth throughout their length. The depth of the channels and the degree of taper of same must be regulated and proportioned to the particular bars under treatment.

One-third to one-half the usual thickness of 55 ordinary splice-bars in the part occupied by the bolt-holes will be found a good proportion. The taper will be regulated by the size and position of the bolt-holes.

For some of the narrower kind of splice-bars it may be well to taper one side or edge only of the channels, as shown in Fig. 2.

The channel form of splice-bars admits of a larger proportion of the material used in their construction being placed above and below the 65 bolt-holes than any other form, and thereby greatly increases the strength of bars against a breaking strain through the said holes; but this form of splice-bars, used years ago, having grooves of uniform breadth and depth running their entire length, deprived the bars of 70 a large quantity of material in the middle, where the two rails meet, thereby causing them to bend and break at this point, where they have the greatest strains to resist, since they 75 bridge over the gap between the two abutting rails.

My system of making the channels broad at the ends of the splice-bars and converging them till their points meet in the middle of the 80 same leaves the bars to which it is applied as strong at the middle as they were before they were grooved, yet preserves the advantages of the channel form at the bolt-holes.

What I claim as my invention, and desire to 85 secure by Letters Patent, is—

1. Splice-bars having the channels or grooves A A', Figs. 1 and 3, said channels running along the face side of the bars through the part occupied by the bolt-holes, said channels 90 beginning at very narrow grooves in middle of the bars at C and broadening upward and downward toward each end of same, and being of uniform depth for their entire length, substantially as described and set forth. 95

2. Angle splice-bars having the channels or grooves A A', Fig. 1, which are full breadth, or nearly so, of the bars at their ends, and converge toward the middle of the same until their points meet at C, said channels being of uniform depth throughout their length and occupying the face side of the bars, substantially as set forth. 100

HOWARD GREER.
